US00D607502S

(12) **United States Design Patent**
Lee et al.

(10) **Patent No.:** **US D607,502 S**
(45) **Date of Patent:** **** Jan. 5, 2010**

(54) **LASER PRINTER**

(75) Inventors: **Son-Young Lee**, Seoul (KR); **Bong-Uk Lim**, Kyunggi-do (KR); **Jun-Won Bae**, Seoul (KR)

(73) Assignee: **Samsung Electronics Co., Ltd.**, Suwon, Kyunggi-do (KR)

(**) Term: **14 Years**

(21) Appl. No.: **29/307,999**

(22) Filed: **May 22, 2008**

(51) **LOC (9) Cl.** **14-02**

(52) **U.S. Cl.** **D18/50**

(58) **Field of Classification Search** D18/36-37, D18/50, 54, 54.1, 55, 19; D14/420-425, D14/463-470; 400/613, 613.1-613.4, 690.1-690.4, 400/691-694

CLAIM

The ornamental design for a laser printer, as shown and described.

DESCRIPTION

FIG. 1 is a top front perspective view of a laser printer showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
